GEORGE UNVERZAGT, OF PHILADELPHIA, PENNSYLVANIA.

Design No. 4,699, dated March 7, 1871.

DESIGN FOR THE BACK OF A CHAIR OR SOFA.

The Schedule referred to in these Letters Patent and making part of the same.

I, GEORGE UNVERZAGT, of Philadelphia, county of Philadelphia, State of Pennsylvania, have invented or produced a Design for the Back of a Chair or Sofa, of which the following is a specification.

The figure in the accompanying drawing represents a perspective view of a chair with an ornamental back, made in accordance with my design.

The back consists of two strips A A, which may be continuations of the rear legs of the chair, and of two or more cross-pieces or braces B B, connected to the said strips.

Both the strips A and cross-braces are grooved, ribbed, or otherwise ornamented, and the said strips and upper brace cross and project beyond each other, as shown, so as to form projecting ends a a.

Rosettes or other ornaments b may be arranged at the point where the strips A and upper brace cross each other, but this is immaterial, and forms no portion of my design.

Another feature of the design is the ornaments C and D, secured to the cross-pieces at the center of the back of the chair, and which are of a character too clearly shown in the drawing to need description.

The design is as applicable to the backs of sofas and settees as to chairs.

Claims.

1. The design for the back of a chair or sofa, consisting of strips A and cross-pieces B, connected together and crossing each other substantially as described, and as represented in and by the accompanying drawing.

2. The design for the ornaments C and D, for the back of a chair or sofa, substantially as shown and described.

In testimony whereof I have signed my name to this specification in the presence of two subscribing witnesses.

GEORGE UNVERZAGT.
